METHOD OF LASTING SHOES

Filed Oct. 15, 1931

UNITED STATES PATENT OFFICE

JACOB S. KAMBORIAN, OF WEST NEWTON, MASSACHUSETTS, ASSIGNOR TO NORTHERN MACHINE CO., INC., OF BOSTON, MASSACHUSETTS, A CORPORATION OF MASSACHUSETTS

METHOD OF LASTING SHOES

Application filed October 15, 1931. Serial No. 568,922.

This invention pertains to the manufacture of footwear, and relates more particularly to devices adjunctive to the shoe lasting process and to a novel process of lasting.

In my copending application Serial No. 515,921, filed February 16, 1931, I have disclosed one desirable method of lasting shoes in which the material of the upper at the end portion of the shoe is effectively flattened and leveled and is permanently secured in place by means of adhesive instead of tacks, staples, or other independent fastener elements commonly employed.

10 In said application I disclosed the use of a normally inactive adhesive applied before lasting to the edge of the toe box or other appropriate part and which was activated during the lasting process so as to become adhesive and to secure the adjacent parts of the shoe together. While the process therein described represents a substantial advance over prior methods, it recommends the use of a toe box having an adhesively 20 coated flange which overlaps the bottom of the insole to a substantial extent, said flange being depended upon to supply the necessary adhesive for uniting the shoe parts, but for some kinds of shoe this overlap of 25 the toe box flange may be undesirable and, furthermore, the operation of preparing the toe box, including the application and pre-drying of the cement, adds materially to the cost of the shoe,—the latter objection.

30 Applying with equal force to the application of the cement directly to the edge of the upper, suggested as an alternative procedure in my aforesaid application. I have also previously accomplished desirable results by applying a hot fluid adhesive of 35 quick setting character to the opposed surfaces of the shoe parts at the toe or heel to hold them in lasted position, but while effective, this method is objected to by some operators by reason of the difficulty involved in applying the fluid adhesive to the shoe bottom without daubing the exposed portions of the upper.

40 In accordance with the present invention I avoid all of the features of my prior

processes which might by any possibility be considered as disadvantageous, while retaining their desirable characteristics, so that my present improved lasting process is thoroughly practical from the commercial standpoint, while at the same time further reducing the cost of shoe manufacture.

55 In the accompanying drawing I have indicated certain desirable steps in my improved lasting process, together with devices adjunctive thereafter, all by way of example and without limiting intent.

In the drawing,

Fig. 1 is a plan view of an adhesive leaf 60 employed in the practice of my improved process;

Fig. 2 is a fragmentary plan view of the toe end portion of a shoe, showing the application of one of my adhesive lasting leaves to the shoe prior to the final leveling 70 of the upper material;

Fig. 3 is a similar view, to smaller scale, showing the edge of the upper at the toe wiped inwardly over the adhesive leaf and secured by the adhesive to the insole; 75

Fig. 4 is a vertical section through apparatus useful in activating my improved adhesive lasting leaves just prior to application to the shoe bottom;

Fig. 5 is a fragmentary plan view of the 80 device of Fig. 4 with the cover removed;

Fig. 6 is a vertical section substantially on the line 6—6 of Fig. 4;

Fig. 7 is a diagrammatic elevation, to small scale, partly in section, illustrating 85 apparatus suitable for use in preparing my improved adhesive lasting leaves;

Fig. 8 is a plan view of a leaf strip consisting of leaves of a shape different from that shown in Fig. 1; and 90

Fig. 9 is a section, to large scale, on line 9—9 of Fig. 1.

With the intended object in view, I employ a normally inactive adhesive which is furnished to the laster in the form of a dry sheet or film, the sheet material preferably being so prepared that portions of a size and shape suitable for use in an individual shoe are readily available to the operator. I have sometimes referred to such individual 100

portions as "toe stamps", but since the invention is not in any sense necessarily limited to the lasting of the toe portion of the shoe, I prefer to refer to such individual portions of the adhesive material as "lasting leaves", such portions being flexible, thin, and leaf-like in character.

The lasting leaves thus employed may consist of homogenous pieces of sheet adhesive of suitable character and normally stiff or at least strong enough to permit ready handling, and of sufficient thickness and substance to furnish the requisite charge of adhesive for use in a shoe, or, if preferred, the adhesive film may be furnished in the form of a coating or an impregnant upon or within a sheet of a carrier material, for example, paper, cloth, or the like. In the latter case, it is preferred to perforate, make foraminous, or otherwise reduce the bulk of the carrier material in order to avoid adding undue bulk to the toe material of the shoe and, more important, to ensure a direct union of the meeting parts of the shoe by the cement rather than through the interposed carrier material. The cement or adhesive employed may be of any suitable character adapted to become adhesive through the application of solvent, heat, or both, and preferably setting very rapidly after incorporation in the shoe. Thus I may employ a cellulose derivative, for example, cellulose nitrate, or a compound thereof, either in dry sheet form of homogeneous character or applied as a coating or impregnant to cloth, paper, or the like, and adapted to be made sticky by exposure to acetone or other solvent, either in liquid or vaporous form. Alternatively I may use Burgundy pitch, camar gum, or other thermoplastic cement, either in the form of homogeneous sheets, or coating or impregnating a suitable carrier material.

For convenience I prefer to prepare the adhesive material in the form of strips of proper width and incised in such a way as to facilitate tearing off pieces of approximately the shape of the end portion of the shoe, such pieces, as above referred to, being hereinafter called lasting leaves.

In preparing my sheet adhesive, assuming for illustration that it is to consist of a carrier sheet coated or impregnated with the selected adhesive, I first preferably prepare long strips 5^a of the sheet material, which for convenience may be coiled or rolled, and after drawing the strip through a bath of the adhesive, previously rendered fluid by solvent, heat or the like, I allow the strip to dry; then slit or perforate it at the proper points to form lines or areas of weakness to facilitate tearing off sections of the desired shape and then preferably reroll or fold it for use. Preferably perforated sheet material is employed, and when this is drawn

through the adhesive bath and dried, it has a surface coating C of adhesive (Fig. 9) together with uniformly distributed areas B consisting of homogeneous films of the adhesive adapted when in use directly to unite the opposed shoe parts between which the leaf is placed. Obviously for best results the perforations should form a large percent of the total area of the material, but this may be limited by the necessity of providing sufficient of the carrier material to furnish the desired strength and stiffness for handling. If desired and in order to save adhesive, the slitting operation, whereby portions of the strip are usually removed in order to produce leaves of the proper shape, may be performed before running the sheet material through the adhesive bath, although if the carrier sheet be thin and easily broken, it may be desirable, as above described, to delay the slitting operation until after drying.

In using the novel adhesive in the lasting operation the shoe upper 1 (Fig. 2) is first pulled over according to usual methods and the sides are lasted. The pulling-over tacks at the toe are then removed and, in accordance with a preferred method, the projecting margin of the lining is trimmed away substantially flush with the bottom of the inner sole at the toe, the edge of the toe box, if such be used, either being trimmed off at this time with the lining or, if left to project over the insole, being furnished with notches in its edge before assembly with the other parts, as more fully described in my prior application. The operator now wipes in the marginal portion 2 of the upper (and the toe cap, if the edge of the latter is to overlap the sole) by means of the bed lasting wipers in usual fashion. The wiper plates are then withdrawn and lifted and, if desired, the central portion of the wiped-in material may be shaved off. The operator now takes one of the previously prepared lasting leaves 3 (Figs. 1 and 2) which, if comprising a solvent adhesive, has just been activated by the proper solvent to make it sticky, and introduces it between the inner sole 4 and the partially lasted overlying toe portion 2 of the upper. A heater plate (not shown) as described in my aforesaid application, may now be laid upon the pleated material of the upper at the toe, and the bed lasting wipers are lowered onto the edge of the plate and left until the adhesive furnished by the lasting leaf 3 has been driven by the heat and pressure into the interstices of the opposed shoe materials and has set firmly enough to hold them in position when the pressure is removed. Usually it is sufficient to leave the parts in position under pressure while the operator is completing the heel lasting, which, if desired, may be accomplished in a similar fashion.

After the wiper plates are lifted and the heater removed, the marginal portions of the upper are firmly held in lasted position by the interposed adhesive, whether the latter be in the form of a homogeneous film, or consist of adhesive coating or impregnating an interposed carrier. When the box toe flange intervenes between the inner sole and the upper, its notches permit sufficient direct adhesion of the inner sole and upper or, if desired, lasting leaves may be introduced both below and above the box toe flange, thus providing additional strength.

When a thermoplastic adhesive is used, the lasting leaf may be interposed between the shoe parts in dry, non-adhesive condition and rendered active solely by the warmth of the heater device. On the other hand, when a solvent adhesive is employed, I preferably make the lasting leaf active or sticky immediately prior to its introduction into the shoe by the use of a suitable solvent as above described. In accordance with one arrangement I pass the strip 5 (Fig. 5) of united lasting leaves through a chamber containing solvent, preferably wetting the strip with liquid solvent and then permitting it to stand or mull in an atmosphere of the solvent vapor for a time sufficient to permit thorough impregnation of the solvent without excessive surface wetting. Then when the lasting leaf is torn from the end of the strip, its surface is not excessively sticky, and it is still stiff enough for ready manipulation. Thus little, if any, of the cement adheres to the fingers of the user and danger of daubing the exposed parts of the shoe upper is substantially eliminated.

In Fig. 7 I have diagrammatically indicated a desirable sequence of steps in preparing the adhesive material. Thus a carrier strip 5^a of paper, cloth, or the like of predetermined width is conveniently furnished in the form of a roll 6,—(the material preferably being foraminous or perforate) and the roll is mounted upon a suitable support 7 to facilitate unwinding. The material is pulled off from the roll and drawn through a receptacle 8 containing the selected adhesive in liquid form and after proper coating or impregnation the material is caused to emerge from the receptacle and dried, either by exposure to the atmosphere alone or with the assistance of artificial currents of air or the like. After drying, the strip of material passes through a suitable device 9 operating to punch, cut or otherwise shape the individual leaves 3 by the production of indentations, incisions, or the like, defining lines of separation or weakness and/or areas of weakness in the material such as to define and to facilitate tearing off sections of proper shape. After this operation the material preferably is wound to form a roll ready for use by the laster.

In Fig. 5 one desirable form of strip is indicated, the perforated sheet material having substantially parallel edges 11 and 12, and at regularly spaced intervals having V-shaped incisions 13 merging into the curved incision 14 so as to leave openings 15 along the center line of the strip. The lateral ends of the incision 13 reach nearly to the edges 11 and 12 of the strip so that at the points 16 and 17 areas of weakness are formed, permitting successive sections of the strip to be torn off easily. Thus by tearing the strip at the points 16 and 17, successive lasting leaves 3, as shown in Fig. 1, result, the curved edge 14^a of the leaf being adapted to fit into the toe portion of the shoe bottom, while the V-shaped notch 15^a reduces the bulk of the material at the end of the shoe. In preparing the adhesive material as above described the surfaces of the strip are coated with the adhesive, and this adhesive extends across each of the perforations 18 in a continuous homogeneous film.

When the adhesive is of a nature requiring solvent to make it stick, I preferably furnish the laster with apparatus such as herein illustrated in Figs. 4, 5 and 6, or its equivalent, for preparing the leaves just prior to the lasting operation. This apparatus comprises a receptacle 19 adapted to hold a body of liquid solvent 20 and preferably having clamping means 21 and 22 for attaching it firmly to a bench or other support. The receptacle preferably is furnished with a tight fitting cover 23, removably held in place, as by pins 24, engaging bayonet slots 25 in the edge of the cover. The receptacle has a window 26 at one end in which is arranged a guide roll 27 over which the coated strip 5 passes, being drawn off from a properly supported supply roll, not shown. Preferably the cover of the receptacle has an opening through which passes a vertically slideable rod 28 provided with a knob 29 at its upper end and normally held in elevated position by a spring 30. Below the cover a guide sleeve 31 is secured to the rod 28, said sleeve having a passage for the strip 5 and being movable downwardly by depression of the knob to carry the strip 5 below the surface of the liquid solvent. Preferably the receptacle is provided with spaced guide partitions 31^a disposed at opposite sides of the sleeve 31 and with a guide trough 31^b extending upwardly from the bottom of the receptacle toward an exit opening 32 in the cover 23. The strip of material emerges through this opening 32, after being activated by the solvent, and to facilitate tearing off the forward leaf from the strip I preferably provide the receptacle with an upstanding tear pin 33 projecting above the level of the cover just beyond the opening 32.

In using this apparatus the strip 5 passes through the opening 26, then through the sleeve 31 and then out through the opening 32. The operator depresses the knob 29 at 5 suitable intervals so as to immerse the strip for a short time in the liquid solvent, but upon release of the knob the strip is raised to the position shown in full lines in Fig. 5. The receptacle is of a length substantially 10 greater than that of a single lasting leaf so that a plurality of such leaves are always within the receptacle; and as the receptacle is substantially closed and as the solvent is usually volatile, thus providing an atmosphere 15 heavily laden with fluid vapor above the liquid level, the leaves are subjected to a prolonged mulling action in this vapor atmosphere after their initial wetting with the solvent, thus ensuring their thorough 20 impregnation by the solvent without unnecessarily softening the exterior surface of the leaf or rendering it too sticky or flabby for handling.

Assuming that the exposed end leaf of 25 the strip has been properly activated and projects from the opening 32, the operator seizes this endmost leaf 3^a (Fig. 5) between his thumb and finger, and by first drawing the strip forwardly and downwardly so that 30 the pin 33 enters the foremost opening 15 and then pulling the end leaf 3^a sidewise, he can readily tear it from the strip without disturbing the other leaves forming the strip. The leaf thus removed is now ready 35 for use in lasting and is inserted in the toe bottom as above described.

In Fig. 8 I have shown a strip 5^b particularly adapted for use at the heel end of the shoe, and it will be understood that strips 40 of this general character, adapted to furnish leaves of any desired shape or size, may be prepared in accordance with the general directions above given and as circumstances 45 may demand, and that the laster may be kept supplied with strips of such widths, leaf configurations, thickness, etc., as may be useful in lasting shoes of different styles or sizes, or opposite ends of the same shoe.

While I prefer to furnish these lasting 50 leaves to the laster in the form of a continuous strip from which he can pull off successive sections as required, I contemplate the preparation of the lasting leaves as individual units which may be arranged in stacks 55 or otherwise for convenient use and which may be activated in any desired manner prior to introduction into the shoe.

Moreover, while I have hereinabove referred 60 to the use of a heater plate as adjunctive to the lasting operation and as useful in flattening the toe material and to facilitate the cementing operation, I contemplate that under some circumstances this heater may be dispensed with, the present 65 invention being of broader scope and gen-

erally inclusive of the use of an adhesive lasting leaf of the type herein described and for the purposes mentioned.

Although certain specific materials, modes of procedure, shapes of parts, etc., have been described as illustrative of the invention, I wish it to be understood that the invention is not thereby limited, but only as defined in the appended claims.

I claim:

1. That method of lasting an end portion of a shoe which comprises as steps wiping in the marginal portion of the upper at said end by means of the wiper plates of a bed laster, retracting said plates, introducing a leaf of adhesive material between the insole and the wiped-in upper material at said end portion, and applying pressure by means of the wipers sufficient to level and set the wiped-in portion of the upper.

2. That method of lasting an end portion of a shoe which comprises as steps wiping in the marginal portion of the upper at said end by means of the wiper plates of a bed laster, retracting said plates, activating a leaf of adhesive material to cause it to become sticky, introducing said leaf of material between the insole and the wiped-in upper material at the end portion of the shoe, subjecting the wiped-in material to heat and pressure to cause the adhesive to penetrate the insole and upper, and retaining the parts under pressure until the adhesive has set.

3. That method of lasting an end portion of a shoe which comprises as steps wiping in the marginal portion of the upper at said end by means of the wiper plates of a bed laster, retracting said plates, introducing a leaf of adhesive material between the insole and the wiped-in upper material at said end portion, disposing a heater member upon the forepart of the shoe bottom, and bringing the wiper plates down upon said heater to cause the latter to level and set the wiped-in portion of the upper.

4. That method of lasting an end portion of a shoe which comprises as steps wiping in the marginal portion of the upper of the shoe at said end by means of the wiper plates of a bed lasting machine, retracting said plates from their advanced position, providing a portion of adhesive film in a form which may be handled, introducing said portion of adhesive film between the insole of the shoe and the wiped-in upper material at said end of the shoe, disposing a pressure member upon the wiped-in material, and holding said pressure member against said material and under pressure by means of the bed lasting wipers until the adhesive film has permanently united the insole and wiped-in upper material.

5. That method of lasting an end portion of a shoe which comprises as steps wiping

in the marginal portion of the upper at said end of the shoe by means of the wiper plates of a bed lasting machine, retracting said plates, providing a lasting leaf comprising a carrier sheet having a film of adhesive thereon, introducing said leaf between the insole and the wiped-in upper material at said end of the shoe, disposing a pressure member upon the wiped-in material and holding said pressure member against said material and under pressure by means of the bed lasting wipers until the film of adhesive has permanently united the insole and wiped-in upper material.

15 6. That method of lasting an end portion of a shoe which comprises as steps wiping in the marginal portion of the shoe upper at said end of the shoe by means of the wiper plates of a bed lasting machine, re-
20 tracting said plates, providing a lasting leaf comprising a perforated carrier sheet having an adhesive film extending across its perforations, introducing said leaf between the insole and the wiped-in upper material
25 at said end of the shoe, disposing a pressure

member upon the wiped-in material, and holding said pressure member against said material and under pressure until the adhesive of said leaf has permanently united the insole and wiped-in upper material. 70

7. That method of lasting an end portion of a shoe which comprises as steps wiping in the marginal portion of the upper at said end by means of the wiper plates of a bed lasting machine, retracting the plates, pro-
75 viding a lasting leaf comprising a film of normally dry and non-sticky adhesive, ex-
posing the leaf to the action of a solvent for the adhesive, introducing said leaf be-
tween the insole and the wiped-in upper 80 portion at said end of the shoe, placing a presser member upon the wiped-in material and exerting pressure upon said presser member by means of the lasting machine
wipers until the adhesive has set and perma-
nently united the insole and wiped-in upper 85 material.
